H. L. SMITH.

COMMUTATOR DEVICE FOR AUTOMOBILE IGNITION SYSTEMS.

APPLICATION FILED MAR. 28, 1919.

1,382,864.

Patented June 28, 1921.

UNITED STATES PATENT OFFICE.

HENRY LUND SMITH, OF PATERSON, NEW JERSEY.

COMMUTATOR DEVICE FOR AUTOMOBILE IGNITION SYSTEMS.

1,382,864.

Specification of Letters Patent. Patented June 28, 1921.

Application filed March 28, 1919. Serial No. 285,863.

To all whom it may concern:

Be it known that I, HENRY LUND SMITH, a citizen of the United States, residing at Paterson, in the county of Passaic and State 5 of New Jersey, have invented certain new and useful Improvements in Commutator Devices for Automobile Ignition Systems, of which the following is a specification.

In the ordinary ignition system of a Ford 10 automobile the commutator contacts are contained in a metal cup covering the end of the cam shaft of the engine and held bearing in a suitable journal formed on the engine frame around said shaft by a spring 15 clip, and the wires from the contacts extend therefrom in a disheveled and unprotected mass, in consequence of which they soon become oil-soaked and caked with grease and dirt and short-circuiting develops. Objects 20 of this invention are to house and thus protect the wires and to provide an arrangement of the parts which will be more neat and shipshape than the present one and so avoid a great part of the trouble and annoyance 25 that have heretofore attended this portion of the ignition apparatus. According to one form of the invention herein shown and in furtherance of an additional object of invention I avoid the use of covered wires, 30 and also provide connections between the commutator and the wires which facilitate quick assembling and disassembling.

In the accompanying drawings,

Figures 1 and 2 are an underneath plan 35 and a sectional view on line 4—4, Fig. 1, of one form of the device constituting my invention;

Fig. 3 is an underneath plan of another 40 form of the device;

Fig. 4 is a transverse sectional view of what is shown in Fig. 3, omitting the housing and on a somewhat larger scale; and

Figs. 5 and 6 are inside plan views of a 45 pair of insulator plates shown in Figs. 3 and 4.

The commutator proper is formed in the present instance by a ring having spaced contacts at its inner periphery, being therefore of the type where the brush *e* on shaft 50 *c* presses in a radial direction against it; this, however, is not indispensable. This ring comprises a metallic annular holder *f* which oscillates in the journal *g* (Fig. 2) on the engine frame, an insulating annulus 55 *h* contained in the ring, and metal contacts *i* inlaid in annulus *h* and having threaded

binding posts *j*, with nuts *k*, projecting outwardly through the holder *f*. The wires *l* (in the present instance having insulating covering, as shown in Fig. 1) are adapted 60 to be attached to these binding posts.

m is a concavo-convex housing, preferably of metal, comprising a cone-shaped body portion *m'*, preferably circular in plan, and a radial extension *m''*. At the inside the 65 body portion *m'* has an annular socket *n* to receive the holder *f* of the aforesaid ring (which may be secured therein against turning in any way, as by the screw *o*), and at the outside, at the apex thereof, it has a 70 central recess *p* in which the usual and aforesaid spring clip *a* has a bearing. When the aforesaid ring, with the wires attached, is assembled with the housing the skirt or marginal flange *q* of the latter lies at its edge 75 close to the face of the engine frame (Fig. 2) and houses the wires as well as the commutator; the wires are kept in a definite or placed disposition by extending into the radial portion *m''* of the housing to the end 80 of which they are secured by the binding posts *r* and nuts *s*. These binding posts (which are suitably insulated from each other) may have nuts at the outside of the housing (not shown) and by them wires 85 leading back to the dash-board of the vehicle may be attached; the latter wires preferably extending through a pipe *v*, attached to the engine, which keeps them together and protected. The extremity of the arm 90 or radial extension *m''* of housing *m* is deflected into a position at an angle to the plane in which the arm projects from the body of the housing, as shown in Figs. 1 and 3, thus to increase the facility of manipulating the securing means, carried by such extremity, for the wiring, and also to reduce the extent of movement of this part of the device and hence the disturbance of that portion of the wiring that extends from said 95 extremity back to the dash board.

To support the contacts of the commutator and the portions *l* of the conductors which are adjacent thereto I therefore have 100 a structure which can be substituted for, and when so substituted will function the same as the ordinary aforementioned cup, and will not only house all parts that are likely to become fouled with grease and dirt but protect them from accidental disarrangement. For oscillating this structure in 105 the timing of the engine the usual operating 110

connection may be attached to an arm *x* projecting from the housing *m*.

In Figs. 3 to 6 the construction is much the same excepting that uncovered wires 5 may be used and provision is made for avoiding the use of tools (as a wrench) in electrically connecting them with the commutator contacts. The commutator and housing, here designated *y* and *z*, respectively, are the 10 same as those already described. The wires 2, which are uncovered, lie in grooves 3 in one of two plates 4, 5 of insulating material, as fiber, which are shaped to fit more or less snugly the interior of the housing *z* and its 15 extension and have openings 6 to receive the commutator; the outer ends of the wires are attached to the binding posts 7 by nuts 8 the same as in Figs. 1 and 2, but their inner ends are soldered to metal terminals 9 inlaid in 20 the plate 4 at points 90° apart and each forming a recessed seat. The plate 5, which may be secured to the plate 4 by a screw or screws 10 or otherwise, retains the wires in the grooves; it also coats with plate 4 to 25 maintain electrical connection between the wires and the several contacts of the commutator, for the posts 11 thereof, projecting outwardly from the commutator, have their heads 12 clamped between the two 30 plates, resting in the seats formed by the terminals 9, so that the commutator in effect forms a unitary structure with the two plates which is in turn unitary with the housing *z* when the parts are assembled as 35 shown in Fig. 3. One advantage of this construction is that after removal of plate 5 the commutator member *y* and what I term the conductor member (being plate 4 and terminals 9 and wires 2 therein) may be

removed, either separately or both together, 40 at the open side of the housing.

Having thus fully described my invention, what I claim as new and desire to secure by Letters Patent is:—

1. In combination, with a concavo-convex 45 housing, a commutator member and a conductor member arranged therein, the commutator member and conductor member respectively including spaced commutator contact and terminal portions held bearing 50 against each other, and one of said members being enterable to and removable from the housing at the concave side thereof independently of the other member.

2. In a commutator device for an automobile ignition system, the combination of a circular series of spaced commutator contacts, and rotatable carrier means for the series of contacts including plates held together face to face and receiving between 60 them and exerting clamping pressure on portions of the contacts.

3. A commutator device for an automobile ignition system including a circular series of spaced commutator contacts, conductors 65 extending outwardly therefrom and each attached to one of them at one end, and a rotatable carrier structure for the contacts including a housing inclosing said contacts and a radially projecting hollow extension 70 inclosing the conductors and having its free end deflected out of the plane of the body portion of said extension, said extremity having means to attach thereto the other ends of said conductors and other conductors to form continuations thereof.

In testimony whereof I affix my signature.

H. LUND SMITH.
